UNITED STATES PATENT OFFICE.

JOHN SWEENEY, OF NEW HAVEN, CONNECTICUT, ASSIGNOR OF ONE-HALF
TO JAMES GRAHAM, OF SAME PLACE.

DESIGN FOR A CURTAIN.

SPECIFICATION forming part of Design No. 15,000, dated May 13, 1884.

Application filed March 26, 1884. Term of patent 14 years.

To all whom it may concern:

Be it known that I, JOHN SWEENEY, a citizen of the United States, residing at New Haven, in the county of New Haven and State 5 of Connecticut, have invented and produced a new and original Design for Curtains, of which the following is a specification, reference being had to the accompanying drawing, forming part thereof.

10 My design consists in a window-curtain having the representation of a blind or shutter thereon.

In the accompanying drawing, (a front view,) A designates the representation of the 15 frame of a shutter; B, that of the slats of said shutter; C, the upper rolled part of said curtain; D, the blank margin of the curtain; E,

the lower edge of the curtain, and F the tassel thereof.

Having thus described my invention, what I 20 claim as new, and desire to secure by Letters Patent, is—

The design for a curtain herein shown and described, the same consisting of the curtain having the ornamentation representing a shutter or blind composed of the frame A and the slats B, substantially as set forth.

In testimony whereof I affix my signature in presence of two witnesses.

JOHN SWEENEY.
